UNITED STATES PATENT OFFICE.

JOSEPH B. CROSBY, OF DUXBURY, MASSACHUSETTS, ASSIGNOR TO HERSEY MANUFACTURING COMPANY, OF SOUTH BOSTON, MASSACHUSETTS, A CORPORATION OF MAINE.

MACHINE FOR SEEDING RAISINS.

SPECIFICATION forming part of Letters Patent No. 729,551, dated June 2, 1903.

Application filed October 30, 1901. Serial No. 80,564. (No model.)

To all whom it may concern:

Be it known that I, JOSEPH B. CROSBY, a citizen of the United States, residing at Duxbury, in the county of Plymouth and State of Massachusetts, have invented certain new and useful Improvements in Machines for Seeding Raisins, of which the following is a specification.

This invention relates to machines for seeding raisins and is an improvement on the machine for which Letters Patent No. 56,721 were granted to me on July 31, 1866.

The invention consists of certain improved details of construction, combination, and arrangement of parts, whereby the operation of removing the seeds from the pulp of the fruit is facilitated and whereby the repair of the pin-cylinder, when damaged by the accidental presence with the raisins of stones or other hard material, can be effected at a minimum of expenditure of time and money.

The invention will be fully described hereinafter, reference being had to the accompanying drawings, in which—

25 Figure 1 is a perspective view of a raisin-seeding machine embodying my invention. Fig. 2 is a vertical longitudinal section. Fig. 3 is an end view. Fig. 4 is a view of the doctor for removing the seeds from the pin-cylinder, and Fig. 5 is a view of an atomizer for moistening the parts of the machine.

By preference the frame consists of cast-iron sides A, held rigidly by bolts A', passing through pipes A'', so that the machine is 35 self-contained. I prefer to make the bearings for the pin-cylinder B a fixed part of the frame and to make all the other bearings of the rotative parts adjustable.

C is the cylinder with an elastic yielding 40 peripheral surface c, preferably of rubber, and the cylinder C is provided with means for accurate and minute adjustment of the surface c to the projecting ends of the pins b, fixed in cylinder B in rows which are both 45 in planes parallel to the axis of cylinder B and in planes which are at right angles to said axis. The pins are so spaced as not to admit between them seeds of rather less than the average size; but abortive seeds may enter

or will remain in the space between the pins 50 with the fruit-pulp.

It is important that in the delivery of the raisins to the conjoined action thereon of the pin and elastic-surfaced cylinders the raisins should not be superimposed on each other. 55 To this end I make use of an endless carrying-belt D, preferably of rubber, the edges of the upper ply of which run in grooves in edge-guides and over a smooth-surfaced plane, which prevents sag of the upper ply 60 of the belt, which passes over and is drawn by the driven roller or pulley H, the peripheral speed of which should be considerably less than the peripheral speed of the acting ends of the pins in the pin-cylinder, so that 65 the raisins become loosely spaced sufficiently to leave room for the spread of the area of the fruit under the conjoined action of the flattening-roller F and the pin and elastic rollers. 70

Over the upper ply of the carrying-belt I arrange a rotating winged or paddle device E, which can be adjusted toward or from the carrying-surface of the belt D and which for the purposes of this specification I call the 75 "layer-regulator." I prefer to make the wings or paddles e of rubber, so that the fruit will not be injured by the action, which is rapid and in opposition to the carrying motion of the belt. The function of this device 80 E is to permit but one layer of raisins to pass beneath it to the action of the flattening-roller F, which is made adjustable toward and from the belt D and its actuator H. The fruit in passing between the roller F and the 85 belt where it passes over the roll or pulley H will be expanded in area and be lessened in thickness and the seeds will be brought closer to the skin. By lessening the thickness of the fruit the pins b may be less in length and 90 diameter than would be needed if the raisins passed to them in their natural state of plumpness. To prevent raisins from sticking to the spreading and flattening roller F, it is kept moist, and I make use of an adjustable 95 scraper I, and to prevent adhesion of fruit to the belt D, I make use of a similar scraper d. A chute G receives the fruit and is ar-

ranged at such an angle that the fruit gravitates upon the pins *b*, which carry it to the bite of the pins and the elastic cylinder, where the well-known operation of the extrusion of 5 the seeds is effected, and the pulp is left in the spaces between the pins.

In my patent before referred to I made use for removal of the extruded seeds of a fixed stripper or doctor-plate made to be adjusted 10 very closely to the pin ends. This doctor-plate I have improved and rendered more efficient by serrating its acting edge and giving it very rapid short reciprocations by means of suitable mechanism. As the seeds 15 are largely, when extruded, partially held in the clutch of adjoining pins, somewhat as a jewel is set in clamps by a jeweler, the rough edge of the doctor-plate catches the seed and gives it a jar or loosening movement both in 20 right and left directions, as well as in the direction given by the rotation of the pin-cylinder. This improvement results in lessening the ratio of broken seeds and of seeds not broken but forced back between the pins 25 into the pulp and with it removed by the strippers.

The doctor-plate *J* on account of the rapid though short reciprocating motion given it should be made as light as possible and of 30 great stiffness to guard against its edge becoming forced into contact with the pins, which would result in extensive breakage, and means for minute and accurate adjustment must be used to keep the operative 35 edge of the doctor in proper relation to the pin ends. In the drawings this plate *J* is shown as so fixed to the piece *K* that it can be removed and replaced. The piece *K* has rounded end portions which are journaled 40 in each side of the frame, and may also move lengthwise therein. Outside of one of the frame sides a rocker-arm *l* is fixed to the journaled piece *K* and extends downward between ears *x*, fixed to the frame, and is subjected 45 to the control of the adjusting-screws *y*, and by the adjustment of said screws the serrated edge *j* of the doctor-plate is set with reference to the ends of pins *b*, and the surfaces of the rocker-arm *l* slide back and forth 50 in short reciprocations against and between the ends of the adjusting-screws *y*. To give reciprocations to the doctor-plate, a collar *m* is fixed on the other end portion of piece *K*, inside the frame. This collar is provided 55 with a stud carrying a roll *n*, which engages in the operative groove *o* of the cam *O*, which may receive rotation from any convenient source. In some cases it may be found convenient to modify the means for adjusting 60 and reciprocating the serrated edged doctor-plate; but the means I have described are efficient.

It now remains to describe the improved stripper by which the impaled fruit is removed from the pins and gravitates into any suitable receptacle or preferably upon an

endless carrying-belt, in which case opportunity is afforded for proper treatment looking toward prevention of sugaring of the seeded fruit.

The strippers *P* are made to fit easily between the pins in the spaces which extend around the cylinder. They are made in the form of a crescent, the inner edge of which fits the surface of the brass coating of the 75 pin-cylinder. The outside of the stripper varies from crescent form by a circular extension *p*, which seats and fits in a groove *q* in the bar *Q*, which is fastened to the frame below the pin-cylinder. To hold the strippers to their work and at the same time have them easily removable for cleansing or exchange or other purpose, I secure to bar *Q* another bar *R*. When this bar is fixed against the circular extensions of the strippers, they 80 are held; but when it is removed any one or all of the strippers can be taken from the machine, as desired.

At intervals during a day of operating and when the fruit-supply to the machine has 90 been shut off and no fruit is left on the pins or elsewhere it is well to wash all parts with a solution of bicarbonate of soda to neutralize the acid of the fruit and to clear off particles of adhering skin and pulp. This bath 95 should be succeeded by one of clear water unless the machine is to remain idle for some time. For cleaning the pin-cylinder I employ a rotary brush *S*, adjustable toward and from the pin-cylinder, and surround the brush 100 with a tank for holding the cleansing fluid.

Experience has shown that to produce the best results it is necessary to keep the parts of the machine which come into contact with the fruit moist with water. Heretofore the 105 application of water has been crude, the methods employed giving too much or too little, and sometimes parts of the machine suffer from flooding and others from drought. I have found that the supply of moisture needed is uniformly, easily, and economically effected by making use of atomizing apparatus in combination with any or all of the parts of a raisin-seeding apparatus. I prefer to have the compressed-air supply and the water-supply proceed from sources outside of the seeder, which is best not encumbered with them; but the issuance-nozzles from which the atomized water is delivered should be so many and so connected with the seeder 110 and so directed that all parts needing moisture will receive the atomized water to exactly suit the moistened areas.

To moisten the upper surface of the carrying-belt, I atomize the lower ply as it moves 115 onward to become the upper ply, atomize the surface of the elastic-surfaced roll where it approaches the bite with the pin-cylinder, atomize the pin-cylinder from behind the strippers to the line where the chute delivers 120 the raisins to the pins, and atomize the compressing-roll, the delivery-chute, and the face 125 130

of the doctor-plate. Each atomized delivery can be easily adjusted as to volume delivered and as to area and location of delivery. The important matter is to provide for more than 5 enough atomization and then regulate so as to have no excess. Thus the fruit will show no excess of moisture and the machine will give better results. There are many good forms of atomizers between which there is 10 little choice, and the employment of any of them in combination with a seeding mechanism I consider as embraced in this part of my invention.

In Fig. 1 I have shown one arrangement of 15 atomizing device in which there is an air-compressor 10 in the form of a bellows operated by a rod 11 connected to a movable part of the machine. From this compressor a series of tubes 12 lead to the several atomizers. As shown in Fig. 4, the atomizer consists of two pipes 13 and 14, each with a perforated conical delivery end, and these pipes are held in proper relation to each other by a coupling, (indicated by 15.) The pipe 13 20 is connected to an air-supply tube 13, and the pipe 14 is supported in a can of water. Two cans only are shown in Fig. 1 (marked 16) and may be supported on the frame of the machine in any desired manner. I have indicated in Fig. 2 the preferred location of the 25 atomizers for the several parts, except that for the belt D, which is shown in Fig. 1; but obviously the location of the several atomizers may be changed, if desired.

30 Having described my invention, I claim—
1. In a machine for seeding raisins, the combination with the seeding-rolls, of a feed-

ing mechanism comprising an endless traveling belt onto which the raisins are delivered, a rotating paddle layer-regulator working 40 above the belt, an inclined chute to deliver the raisins from the belt to the seeding-rolls, a roller coöperating with the belt to flatten the raisins before they are delivered to the chute, and means firmly supporting the belt 45 at the point of engagement with the roller, substantially as set forth.

2. In a machine for seeding raisins, the combination with the seeding-rolls, one of which has circumferential rows of impaling-pins, means to feed the fruit thereto and means to remove the expressed seeds, of a series of crescent-shaped strippers fitting between the rows of impaling-pins and each having a circular extension, a supporting-bar 50 having a groove to receive the extensions, and a securing-bar completing the bearing for said extensions and removable to permit one or more of the strippers to be separately removed from the supporting-bar, substantially as set forth.

3. In a machine for seeding raisins, the combination with the devices for conveying the raisins to and pressing them on the pins of the pin-cylinder, of atomizers arranged in 60 proximity to said devices to supply moisture thereto, substantially as set forth.

In testimony whereof I have signed my name to this specification in the presence of two subscribing witnesses.

JOSEPH B. CROSBY.
